CLAIM

I claim the ornamental design for men's boxer briefs, as shown and described.

DESCRIPTION

FIG. 1 is a front elevational view of men's boxer briefs showing my new design.

FIG. 2 is a front view thereof showing the outside circular pouch

FIG. 3 is a rear elevational view thereof showing the interior mesh-like pouch

FIG. 4 is a back view thereof

FIG. 5 is a right view thereof

FIG. 6 is a left view thereof

FIG. 7 is a top view thereof

FIG. 8 is a bottom view thereof

FIG. 9 is a right front elevational view thereof; and, FIG. 10 is a top back elevational view thereof showing how the inside mesh pouch matches up to the outside "circular pouch".

The evenly spaced broken lines in the drawings depict portions of the men's boxer briefs that form no part of the claimed design. The dash dot lines represent stitching that forms part of the claimed design.
